(57) **CLAIM**

The ornamental design for a bottle, as shown and described.

DESCRIPTION

FIG. 1 is a front-side view of a bottle;

FIG. 2 is a side view of the bottle of FIG. 1; and,

FIG. 3 is a top-side plan view of the bottle of FIG. 1.
The portions of the drawings illustrated in dashed lines, if any, depict portions of the article that form no part of the claimed design. The portions of the drawings illustrated in dash-dot-dot lines, if any, indicate boundaries that form no part of the claimed design.**1 Claim, 3 Drawing Sheets**FIG. 1

FIG. 2

FIG. 3
